DES. 2032

Merritt Peckham, of Utica, N.Y.

Letters Patent No. 2032 - Dated Feb'y 21-1865.

Design for an Agricultural Furnace.

The schedule referred to in these letters patent and making part of the same,
to all whom it may concern:

Be it known that I, Merritt Peckham, of
the City of Utica, County of Oneida and State of New York, have
invented or produced a new and original design for an
Agricultural Furnace, and I do hereby declare that the
following is a full and exact description of the same, reference
being had to the accompanying drawings, in which

Figure 1, represents a front and side view, and

Figure 2, a rear and side view of such furnace,
all in perspective.

A is the stove. B is the circle. C is the casing and
D is the top.

The corners of the stove A are in the form of panel-
ed columns. The panels are fluted and are in high relief on
the circle, as seen in figures 1 and 2. The bottom of the
side plates of the stove have a wavy configuration like
the base of the columns, while what represents the columns
converge towards the centre of the plate as seen in figures
1 and 2. The joints of the top of the stove A and circle B.

DES. 2032

2

and of the said circle and the casing case covered by moulding or beading as seen in figures 1 and 2. The casing is plain with the exception of the joints where the parts of which it is composed are united. The top is composed of concave and convex moulding with what may be called a fillet between, with a like one on the edge, the whole forming a more neat and tasteful design for the purpose designated than hitherto used or invented.

Claim. The design and configuration for an Agricultural Furnace as herein described.

Witnessed,

Edwin Peckham,

Meritt Peckham,

J. T. Peckham,
